UNITED STATES PATENT OFFICE.

STEPHEN SHANAHAN, OF CHARLESTON, WEST VIRGINIA, ASSIGNOR OF ONE-FOURTH
TO J. B. PRAIRIE AND ONE-FOURTH TO J. B. CROWLEY, BOTH OF CHARLESTON,
WEST VIRGINIA.

COVER FOR SERVICE BOXES AND THE LIKE.

Application filed May 16, 1923. Serial No. 639,232.

To all whom it may concern:

Be it known that I, STEPHEN SHANAHAN, a citizen of the United States of America, and resident of Charleston, county of Kanawha, and State of West Virginia, have invented certain new and useful Improvements in Covers for Service Boxes and the like, of which the following is a specification.

10 This invention relates broadly to service boxes, and more particularly to a casing and cover for water and gas service boxes, meter boxes, valve boxes, and the like.

The primary object of the invention is to 15 provide a structurally improved form of cover for curb service boxes and similar enclosures.

A further object is to provide a cover of 20 the character mentioned which is adapted, without attention, to remain in serviceable, readily-operative condition throughout long periods of time.

In describing the invention in detail, reference is herein had to the accompanying 25 drawings, in which—

Figure 1 is a top plan view of the removable cover of a service box casing forming a part of the invention;

Figure 2 is a side view of the same, partially broken;

Figure 3 is a bottom plan view of the same with the spring removed;

Figure 4 is a vertical section of the invention, showing its application, said section being taken substantially on line 4—4, Fig. 3;

Figure 5 is a section on line 5—5, Fig. 3;

Figure 6 is a detail view in bottom plan of the shiftable locking member and the operating cam;

Figure 7 is a top plan view of a modified form of the invention designed as a top or cover for meter boxes, valve boxes and the like;

Figure 8 is an under side elevation of the modified form of removable cover shown in Fig. 7;

Figure 9 is a section on line 9—9, Fig. 8;

Figure 10 is a section of the invention on line 10—10, Fig. 8; and—

Figure 11 is a view similar to Fig. 8, showing the locking bolt in unlocked position.

Referring, first, to Figs. 1 to 6, inclusive,

1 indicates a circular cast-metal cap or cover 55 adapted to seat upon the top of a cast-metal casing 2 which, generally considered, is of tubular form and which is designed for mounting in superposed embracing or enclosure-forming relation to the upper end 60 portion of an upright service box pipe 3 of the general type employed at curbs for housing the usual valves of house-service water and gas lines.

Said cover has formed integral therewith 65 and depending from its under face a pair of oppositely disposed vertical walls 4 which have their lower end portions connected or joined by a flat horizontal member of panel 5. For weight reducing purposes said panel is preferably made of the apertured or skeleton-like form shown in the drawings, but it may obviously be made in non-apertured panel form if desired.

Formed on the cover 1 and located between the walls 4 is a depending hollow boss 6 having a flat under face disposed at a level spaced from the panel 5 a distance suitable for the reception therebetween of a longitudinally shiftable plate 7 which preferably has its lateral edge portions slidable in channels or guideways 8 provided therefor in the confronting inner faces of said walls 4. Said plate 7 is provided with a centrally located aperture 9 of approximately the conventional form of a heart, the purpose of which will presently be described, and formed on one end of said plate is a horizontally disposed locking bolt 10 which is adapted, in sliding movements 75 of said plate, to be shifted into and out of one of two oppositely disposed sockets 11 formed in the casing 2.

A bolt 12, similar to the bolt 10, is formed on the panel 5, the same being adapted to 95 seat in the opposite socket 11 of the casing 2 and to cooperate with said bolt 10 for locking the cover in place on said casing.

Disposed within a socket or countersink 13 which is formed in the cover 1 by the provision of the hollow boss 6 is an angular head 14 formed on a vertical pin 15. Said pin, which has its body portion rotatable in a hole 16 provided therefor in said boss, has its lower end portion projected through 100 and rotatable in the panel 5 and is secured against chance withdrawal by a cotter pin 17 or other equivalent means which is di-

rected through an eye in the end thereof. Suitably mounted in non-rotatable relation to an intermediate portion of said pin, as upon a squared portion 19 thereof, is a cam 5 18 which lies within the heartshaped aperture 9 of plate 7 and which, through rotation of said pin, effected by means of a socket wrench or other suitable tool applied to the head 14, is adapted to effect forward 10 shifting of the plate 7 for projecting the bolt 10 of the latter into the thereto-adjacent socket 11 of the casing 2 and to maintain said plate in its said forwardly thrust position. Depending lugs 20 and 21, respectively, carried by said bolts 10 and 12, are connected by a retractile coil spring 22 which tends normally to maintain the plate 7 in its retracted position, shown in Fig. 3 of the drawings. Obviously, forward shifting of said plate is effected against the tension of the spring 22, and, when the cam is rotated from its said advanced position, said spring acts to retract said plate to a position wherein its bolt 10 20 is wholly withdrawn from the adjacent socket 11.

In the modification illustrated in Figs. 7 to 11, inclusive, a casing 2^a having an internal top flange 23 is employed, the same 30 being designed for receiving a cap or cover 1^a in seated relation to supporting lugs 24. The bolt 12 of the structure shown in Figs. 1 to 6 is omitted and in place thereof a lug 25 is formed integral with said cover 1^a, said lug being adapted to closely underlie the flange 23 of the casing 2^a in a position diametrically opposite a depending lip 26 carried by said casing. The bolt 10^a of a 40 slidable plate 7^a is designed to be shifted into and out of closely underlying relation to said lip 26, as shown in Fig. 10, said bolt being adapted to cooperate with said lug 25 for locking the cover in place. Except as described, the modified form of structure 45 disclosed in Figs. 7 to 11 substantially corresponds throughout to that shown in Figs. 1 to 6 hereinbefore described. Said modified form is designed for use in covers of large size, as, for instance, tops for meter boxes and valve boxes.

In order to provide for accurate positioning of the cap 1^a on the casing, the seat formed in the latter is of a non-circular form, and the cap is shaped to correspond thereto, as shown.

The parts of the structure, except the

slidable plate 7, are preferably made of cast iron, while said plate is preferably made of brass or other non-corrosive metal, thereby to reduce the liability of the movable parts to become inoperative from accumulation of rust.

What is claimed is—

1. In a cover for curb boxes and the like, a casing having internal sockets in diametrically opposite sides thereof, a cap for seating upon said casing, a fixed support suspended from the under side of said cap, an apertured plate slidable upon said support, a locking bolt formed on said plate and shiftable with movements of the latter into and out of one of said sockets, a fixed member carried by said support for seating within the opposite socket, resilient means normally holding said plate retracted, a pin projected downward through said cap and rotatable in the latter, and a cam carried by said pin within the aperture of said plate, said pin being adapted to be actuated by rotation of said pin to effect shifting movement of said plate against the tension of said resilient means.

2. In a cover for curb boxes and the like, a casing having internal sockets in diametrically opposite sides thereof, a cap for seating upon said casing, a fixed support suspended from the under side of said cap, opposite vertical walls depending from the under side of said cap, a horizontal member integral with and connecting the lower ends of said walls, a fixed bolt carried by said member adapted to seat within one of said casing sockets, a depending boss formed on the cap, a plate slidable horizontally between said member and said boss, a locking bolt carried by said plate at the side opposite said fixed bolt and adapted in the advanced position of said plate to seat in the opposite casing socket, resilient means normally holding said plate in retracted position, a headed pin extending vertically through and rotatable in said boss, and a cam carried by said pin and rotatable therewith whereby said plate is shifted to and from its advanced position.

In testimony whereof, I affix my signature in presence of two subscribing witnesses.

STEPHEN SHANAHAN.
